MAGNETIC TAPE TRANSPORT

Karel Jacobs, Huntington Beach, Agazio S. Gugliotta,
Hacienda Heights, Alexander M. Bradley, Huntington
Beach, Charles E. Wallace, Palos Verdes, and Robert C.
Mallon, La Habra, Calif., assignors to Vanguard Data
Systems, Inc., a corporation of California

Filed Dec. 9, 1968, Ser. No. 14,842

Term of patent 14 years

Int. Cl. D14—01

U.S. Cl. D26—14

FIG. 1 is a front elevational view of the magnetic tape transport;

FIG. 2 is a bottom plan view of the magnetic tape transport of FIG. 1;

FIG. 3 is a left elevational view of the magnetic tape transport of FIG. 1;

FIG. 4 is a right elevational view of the magnetic tape transport of FIG. 1; and

FIG. 5 is a top plan view of the magnetic tape transport of FIG. 1.

We claim:

The ornamental design for a magnetic tape transport, substantially as shown.
